RING PULL

Charles J. Stiff, Arlington, Mass.

Application January 11, 1939, Serial No. 250,276

5 Claims. (Cl. 16—126)

My present invention relates to hardware and like articles of manufacture, more particularly furniture and cabinet hardware, especially ring pull devices. It aims to provide for such articles and devices a simple construction whereby the non-continuous or split rings thereof have their adjacent ends held against objectionable separation, together with novel methods of making and assembling such devices.

10 In the drawing showing by way of example one embodiment of the invention and illustrating means for practising the method thereof:

Fig. 1 is a front elevation of a ring pull assembly;

15 Fig. 2 is a side elevation of the same, showing the device installed as upon a drawer, door or the like;

Fig. 3 shows the ring of Figs. 1 and 2 prior to application of the cooperating supporting element;

20 Fig. 4 is a plan of such supporting element or strap, showing the latter before being bent into ring-enclosing position, looking at the inner face of the enclosing portion of the strap;

Fig. 5 is a sectional view through the assembled strap, as on the line 5—5 of Fig. 2, with the ring in elevation;

25 Figs. 6 and 7 are sections as if on the line 6—6 of Fig. 5, respectively showing the ring in its rest or down-hanging position and its use or out-standing position;

Fig. 8 illustrates a step in the formation of the ring in accordance with a method of the invention; and

30 Fig. 9 is an enlarged view corresponding to a portion of Fig. 6.

Devices of the class described, that is, ring pulls in general, and particularly for cabinet and furniture hardware, are of two main types, with reference to their construction. In one type the ring is an integral or continuous element, generally formed by casting the metal or other material. This type is relatively expensive, involving various finishing operations, and any decorative formations on these rings generally must be applied 40 separately after the ring is formed, at additional cost. In the other main type of ring pull, the ring is formed from a piece of stock, usually a metal wire, rod or bar, or a sheet or strip, in any such instance the ring-forming piece being fashioned 45 into ring shape, generally by bending it into ring form and bringing the two ends substantially together in alinement. This type of ring pull has heretofore been subject to the main objection that the adjoining ends are likely to separate when 50 the ring is pulled in use. Such tendency may be 55

reduced by brazing or welding the ends but such treatment is itself expensive and also necessitates additional finishing operations. Moreover, end separation still may occur, as under sudden or heavy pulls.

5 My invention is concerned with this non-continuous, split, or jointed type of ring pull devices and provides a method and means whereby the adjacent ends of the ring are securely held against undesirable separation in use, at a relatively low cost.

10 Referring now more particularly to the drawing, the ring or ring element 10 of the several figures may be formed of any suitable material, generally metal, preferably a non-ferrous or non-corrosive metal or alloy such as brass or other material adapted for furniture hardware. The stock from which the ring is made usually is cut from a supply in wire or bar form or may be taken from a sheet or strip. The two ends 11 15 and 12 of the piece are brought together into substantially abutting relation and in alinement, forming a joint portion or section indicated as a 20 whole by the numeral 10a, Fig. 3.

25 This joint section is fashioned for reception, desirably with capacity for swinging movement, in a supporting or attaching element or strap to be referred to. In accordance with my invention this joint section additionally has formed thereon lateral abutment formations such as the lugs 13, 30 14 of the figures, one on each end of the ring. These may be provided in various ways, but in the interest of cost reduction I prefer to die-stamp the joint section of the ring, as illustrated in Fig. 8. These abutments or lugs 13, 14 may be 35 at any location around the cross sectional periphery of the ring and may lie within the contour of the ring material or project beyond it. Conveniently, and in the illustrated example they are 40 at the inner peripheral portion of the ring and terminate substantially in line with the inner ring circumference, lateral spaces or seats 15, 16 being provided between the lugs and the material of the ring beyond them. Depending somewhat on the size of the ring the lugs may be at or 45 substantially at the extreme ends of the ring so that, as illustrated, the two lugs stand closely together substantially as a single split tongue or lug element.

50 The cooperating supporting or attaching strap 17 is indicated as a whole by the numeral 17. One such strap is shown separately, prior to assembly, in Fig. 4, and upon a larger scale, in assembled condition, in Fig. 9. This element also may be 55 of any suitable hardware material, generally

metal, which may be similar to that of the ring or otherwise, the metal or other material being sufficiently ductile to permit of the strap being bent into ring enclosing position, as illustrated in Figs. 1, 2 and 5 to 7.

Such strap 17 includes an anchoring portion 18 of substantially cylindrical or any other desired form. In the illustrated example said anchoring portion is drilled and tapped as at 18a

10 for the reception of an anchoring screw 19 as represented in Fig. 2. It will be understood, however, that the anchoring portion of the strap may be otherwise formed for reception and securement in the wood or other material D, Fig. 2, of the drawer, door or the like on which it is to be used; as for example, the thread on the butt of the strap need not be of the internal or female type illustrated.

The strap 17 further comprises a ring receiving, bearing or enclosing portion 20, having its outer end beveled or otherwise shaped, as indicated at 20a, for conforming reception in a like shaped seat or formation 18b at the neck or inner end of the anchoring portion 18. Thus 25 when the enclosing portion of the strap is bent about the ring its end portion 20a conforms substantially to the outer contour of the anchoring portion, as clearly seen in Figs. 2, 6 and 7. If desired the strap may have a laterally projecting flange or spaced projections 18c at the proper intermediate point to limit the extent of insertion of the anchoring portion. These projections generally take against a base plate or washer 19a at the outer face of the part to which the 30 ring pull device is to be attached, as represented in Fig. 2.

Further in accordance with my invention I provide on the bearing or enclosing portion 20 of the strap, at the inner face thereof, spaced walls 40 or abutment formations 21, 22, for cooperation with the lugs or abutment elements 13, 14 of the ring. Opposing faces of these walls are spaced, in the direction crosswise of the strap, sufficiently to receive said lugs or abutment formations 13, 45 14 between them. These abutment formations 21, 22 on the strap may be in the nature of raised portions or they may be provided by removing or omitting material from the strap, so as to provide between said formations a channel or 50 recess 23 preferably having defining end walls 24 and 25, or in some cases the bottom wall of this recess may be tapered into the adjacent portions of the strap. The strap as described may be formed by casting, or by stamping, pressing, 55 dieing, cutting or otherwise shaping it from the blank material or stock, which may be in the form of a rod, bar, sheet or strip.

In assembling the two main elements of the ring pull device, the strap 17 is placed transversely of the ring 10, with the lugs or abutment formations 13, 14 of the latter received between the walls 21, 22 of the strap and in the intervening channel or recess 23 thereof. The enclosing portion 20 of the strap is then bent around the 60 ring and its end 20a brought down into matching relation with the anchoring butt 18 of the strap, as seen in Figs. 2, 5 to 7 and 9.

In this assembled condition it will be noted, particularly with reference to Fig. 5, that the 70 spaced walls or abutments 21, 22 of the strap stand at opposite sides of the ring lugs or abutments 13, 14, in abutting or substantially abutting relation to them, thus positively and securely interlocking the ends of the ring and preventing 75 separation of the latter, in the direction peripher-

ally of the ring, under any ordinary or indeed extraordinary pulling action to which the ring may be subjected. It will further be noted, particularly with reference to Figs. 6, 7 and 9 that the end walls 24 and 25 of the strap recess 23 also cooperate with the locking lugs 13, 14 of the ring ends, in the manner of limiting stops for the swinging movement of the ring relative to the strap.

In its normal or rest position, as in Figs. 2, 10 6 and 9 the ring assumes a down-hanging position, substantially vertically, wherein its lugs 13, 14 abut the end wall 25 of the strap recess. When the ring is lifted for use, its joint section moves pivotally within the enclosing bearing portion of the strap, the lugs 13, 14 moving along the strap recess 23 until they abut its other end wall 24 which accordingly defines the elevated or use position of the ring, substantially as in Fig. 7. The recess 23 of the strap may be made of any 20 length, or angular extent in the assembled position of the strap, to afford the desired angle of movement for the ring. In the above description of the ring I have referred to a method of making the latter which includes an operation of 25 stamping or dieing the joint section 10a, including in this operation the formation of the abutments or lugs 13, 14. The condition of a ring immediately following such die-stamping operation is illustrated in Fig. 8. As there seen the 30 metal died from the joint section is left attached as a web or so-called flash 10b, 10c. Completion of the ring is effected merely by breaking or clipping off this flash, as by a tool or die shaped for the purpose. The completed ring 35 may then be assembled with its strap in the manner already described, or the rings and straps may be supplied separately to the furniture or other manufacturer for subsequent assembly by him, either when the pull devices are to be installed on an article of furniture or the like, or previously. It will also be understood that in connection with the dieing or stamping of the ring, or separately, the exposed face or the entirety of the ring may be provided with decorative 40 formations and designs appropriate for articles of the class referred to. The invention, as stated, is applicable to ring pulls and ring devices in general, including not only furniture hardware, but plumbers' hardware and various 45 other lines.

My invention, either as to article or method, is not limited to the exemplary embodiment or steps herein illustrated or described, and I set forth its scope in my following claims.

I claim:

1. In furniture and like hardware, a ring pull device comprising, in combination, a transversely split ring formed of a single length of material fashioned to ring form with its ends substantially 60 abutting, a lateral abutment element on each end portion of the ring, a strap to support the ring, said strap including an anchoring portion and a bearing portion adapted to be bent upon itself so as to enclose the end sections of the ring, said 65 bearing portion having at its inner face formations adapted to be received at the opposite sides of the respective abutment elements of the ring, in the bent position of the bearing portion of the strap, positively to lock the ring against separation of its ends in the direction peripherally of the ring.

2. A ring pull comprising a piece of stock formed into a ring with the ends of said piece in adjacent alignment, a supporting strap rotat-

ably to enclose the adjoining ring ends, said strap having an anchoring butt for reception in the material to which the ring pull is to be applied and having a ring-enclosing portion adapted to be turned reversely toward the butt portion so as to enclose the ring ends, the inturned end of said enclosing portion then seating against and conforming with the butt portion, spaced wall means at the inner face of the enclosing portion of the strap, and means on the respective ring ends receivable between said wall means, in the inturned position of the enclosing portion of the strap, for interlocking purposes.

3. A ring pull comprising, in combination, a non-continuous ring having its ends in adjacent alinement, a lateral lug on each ring end, a supporting strap to enclose the ring ends, said strap having an anchoring butt for reception in the material to which the ring pull is to be applied and having a ring-enclosing portion adapted to be turned reversely toward the butt portion so as to enclose the ring ends, the inturned end of said enclosing portion then seating against and conforming with the butt portion, and spaced formations on the strap adapted to stand at opposite sides of the ring end lugs, in the inturned position of the enclosing portion of the strap, to hold the ring against separation.

4. A ring pull comprising an elongated piece bent into the form of a ring with the ends of said piece in adjacent alinement, a supporting

strap rotatably to enclose said adjoining ring ends, said strap having an anchoring butt for reception in the material to which the ring pull is to be applied and having a ring-enclosing portion adapted to be turned reversely toward the butt portion so as to enclose the ring ends, the inturned end of said enclosing portion then seating against and conforming with the butt portion, and abutment formations on the strap and on the ring ends, said formations cooperating in the inturned position of the enclosing portion of the strap so as to lock the ring ends against separating movement, and permitting swinging movement of the ring in which the ring ends move rotatively within said enclosing portion of the strap.

5. A ring pull comprising, in combination, a split ring having its ends in adjacent alinement, a lateral lug on each ring end, a supporting strap having a portion to enclose the ring ends, and a recess at the inner face of the ring-enclosing portion of the strap, of a width to receive the lugs on the ring ends and hold the latter against separation and of a length to afford the desired swinging movement for the ring between down-hanging and out-standing positions, the end portions of said recess providing limiting stops for said ring movement.
